JOHN WOSIEWSKI

BY

Richard B. Deven
ATTORNEY.

UNITED STATES PATENT OFFICE.

JOHN WOSIEWSKI, OF NANTICOKE, PENNSYLVANIA.

FILE-PROTECTOR.

1,349,596.

Specification of Letters Patent. Patented Aug. 17, 1920.

Application filed April 22, 1919. Serial No. 292,000.

To all whom it may concern:

Be it known that I, JOHN WOSIEWSKI, a citizen of the United States, residing at Nanticoke, in the county of Luzerne and 5 State of Pennsylvania, have invented certain new and useful Improvements in File-Protectors, of which the following is a specification.

This invention relates to an improved file 10 guard or protector.

The object of the invention is to provide a simple and efficient file holder and protector which will accommodate files, rasps and similar tools and may be readily applied or 15 removed, being held by friction on the file and requiring no auxiliary fastening means.

With the foregoing and other objects in view, which will appear as the description proceeds, the invention resides in the combination and arrangement of parts and in the details of construction hereinafter described 20 and claimed, it being understood that changes in the precise embodiment of the invention herein disclosed may be made 25 within the scope of what is claimed without departing from the spirit of the invention.

In the accompanying drawings:—

Figure 1 represents a bottom plan view of a file protector constructed in accordance 30 with this invention shown applied.

Fig. 2 is a top plan or front view thereof,

Fig. 3 is a longitudinal central section taken on the line 3—3 of Fig. 1,

Fig. 4 is a transverse section taken on the 35 line 4—4 of Fig. 3, and

Fig. 5 is a similar view taken on the line 5—5 of Fig. 3.

In the embodiment illustrated, the guard or protector constituting this invention comprises a single piece of sheet metal 1 shaped to conform to the shape of the file to be housed therein, being especially designed 40 for use in connection with flat files. This guard or plate 1 has its side edges bent at 45 right angles to form flanges 2 which are designed to engage the opposite side edges of the file F. The smaller end of the guard 1 is bent up to form a point retaining flange 3, said flange being preferably provided 50 with an inturned lip 4 shown clearly in Fig. 3. The rear end of the file guard has a band 5 extending transversely therearound which forms a guide for the file during its insertion and removal and also as a retain-

ing member to hold the file in operative engagement with the guard, coöperating with the lip 4 at its other end for this purpose, hook-like fingers 6 being carried by said band and extending longitudinally relative to said plate for engaging the shoulder of 60 the file.

From the above description, it will be obvious that the file incased within this guard 1 will be protected at its back, side edges and front end as shown clearly in Fig. 2 65 with only one of its serrated or roughened faces exposed.

When it is desired to remove the file, all that is necessary is to slip the guard 1 off, and to apply it the lip is reversed and the 70 file slipped within the guard and held engaged therewith by its front end passing under the lip 4 and by the retaining band 5 which encircles the file near its handle or tank T.

From the foregoing description, taken in connection with the accompanying drawings, the advantages of the construction and of the method of operation will be readily apparent to those skilled in the art to 75 which the invention appertains and while I have described the principle of operation of the invention together with the device which I now consider to be the best embodiment thereof, I desire to have it understood that 80 the device shown is merely illustrative and that such changes may be made as are within the scope of the claimed invention.

Having thus fully described my invention, what I claim as new and desire to secure by 90 Letters Patent, is:—

A file protector or guard comprising a single piece of sheet metal shaped to conform to the file in connection with which it is to be used, right angular flanges on the 95 side edges of said guard, one end of the guard having a flange with an inturned lip, a band extending transversely around the other end of the guard, and hooks carried by said band and extending longitudinally 100 of the guard to engage the shoulders of a file.

In testimony whereof I affix my signature in presence of two witnesses.

JOHN WOSIEWSKI.
